REFRIGERATOR

Frank H. Ryder, Cobleskill, N. Y., assignor to
 Harder Refrigerator Corporation, Cobleskill,
 N. Y., a corporation of New York

Application November 14, 1932, Serial No. 642,563

3 Claims. (Cl. 62—46)

My invention relates to refrigeration and more particularly but not exclusively to refrigerators of the type in which ice is used as a refrigerant.

In any type of refrigerator, it is quite essential, if perishable foods are to be cooled quickly and maintained at temperatures sufficiently low to effect preservation thereof, that heat be withdrawn therefrom with a fair degree of rapidity. Furthermore, since some foods which are highly perishable, such as milk, require for their effective preservation a temperature considerably lower than others, it is desirable that some of the food storage space be so arranged that the necessary low temperature can be maintained therein at all times.

Since it is ordinarily undesirable and in most cases impossible to store all the food in contact with or in close proximity to the ice, it is necessary so to design the refrigerator that a constant circulation of air automatically takes place therein. For this reason ice storage compartments are usually placed at the top of the refrigerator and extend over all or at least part of the food storage space. By this arrangement the air about the ice is cooled and condensed, whereupon it flows downwardly through suitable openings into the food compartments where it absorbs heat from the food, expands and rises into the icing compartment to be cooled for a repetition of the cycle.

Where the design is such that the cooled air must pass downwardly and the warmed air upwardly through the same opening, circulation is greatly impeded and it is impracticable efficiently to maintain temperatures as low as are desirable and impossible to maintain a milk storage space at a temperature substantially below that of the remaining food storage space.

These disadvantages are quite well overcome in that type of refrigerator having a vertical baffle or partition extending from the front to the back and from a point somewhat above the floor to a point quite near the top. The ice storage space is at the top and at one side, or substantially at one side, only of the partition. The milk storage space is immediately below the ice, and the main food storage space is on the opposite side of the partition and extends from the bottom to the top of the refrigerator.

By this arrangement the cooled air from the ice flows first downwardly through the milk storage space, then under the baffle or partition into the main storage space, upwardly through this space and over the top of the baffle into the ice storage space. Thus it is possible quite efficiently

to maintain the temperature of the milk space substantially lower than that of the main space.

In domestic size refrigerators of this type the ice storage space is usually comparatively narrow and deep and hence the top of the ice itself, especially after some melting has occurred, is considerably below the top of the ice storage space and the warm air return passage at the top of the baffle. It is undesirable to lower this passage or to provide other passages or openings at lower elevations communicating between the ice storage space and the main food storage space because, instead of the desired flow of warm air from the main space into the ice compartment, the cold air from the ice compartment will flow into the main food space thereby robbing the milk storage space and greatly impeding the circulation because of this reverse movement of air.

Because of the comparatively large space which exists between the ice and the top of the ice compartment where the warmed air must enter, and which increases as the ice melts, the warmed air does not flow into contact with the ice until a considerable volume has accumulated not only in the upper portion of the ice compartment but also in the adjacent portion of the food compartment. Hence the rate of circulation and the efficiency of the refrigerator decreases appreciably as the ice melts.

The general objects of my invention, therefore, are to provide a refrigerator of high efficiency having a rapid rate of circulation which will not be substantially affected by large variations in ice volume, and in which a milk storage space can be consistently maintained at a uniformly low temperature.

I accomplish these objects by the novel elements and the arrangements thereof described below and illustrated in the accompanying drawing in which—

Fig. 1 is a front elevational view partially in section and with parts broken away to illustrate the construction of my refrigerator; and

Fig. 2 is a section of Fig. 1 in the plane 2—2.

In the drawing 1 represents my refrigerator generally which comprises the usual casing 2 having heat insulated walls 3 supported on legs 4. A refrigerating compartment 5 is provided across the entire upper portion of the casing. This compartment is understood to be closed by a door 106 (see Fig. 2). The balance of the space within the casing and below the refrigerant compartment is used for food storage and this space is divided into two sub-compartments 7 and 8 by a vertically depending partition or baffle 9 ter- 110

minating some distance, say seven or eight inches, above the interior bottom 10 of the casing. The transverse partition 11 which forms the bottom of the refrigerant compartment and the top of the food compartments is heat-insulated, as is the baffle 9 which depends therefrom.

Where ice 6 is used as a refrigerant it is supported on the usual rack 12 spaced a few inches above the bottom of the refrigerant compartment to provide therebetween a cold air flue or duct 13. Centrally disposed over the smaller food storage compartment 7 is an opening 14 of substantial size in partition 11 which provides a passage for the downward flow of cold air from the flue 13 into the sub-compartment 7. This sub-compartment 7 is designed to store highly perishable foods, while sub-compartment 8 is designed to store less perishable foods. Both compartments are provided with shelves (not shown) supported on the angles 15.

The bottom of the refrigerant compartment at the right hand side terminates somewhat short of the inside of the refrigerator to provide an opening 16 of substantially smaller cross sectional area than the opening 14 for the upward flow of warmed air, and a heat-insulated baffle 17, spaced from the side wall of the refrigerator, extends upwardly from the bottom of the refrigerant compartment to a point intermediate the top and bottom of the compartment. This point is preferably about midway between the top and bottom or even slightly below the mid point and, in any event, the baffle should extend upwardly to a point somewhat above the bottom of the refrigerant compartment and terminate at a point substantially removed from the top thereof. This baffle together with the sides of the casing form a vertically extending warm air duct 22. Between the top of the baffle 17 and the top of the refrigerant compartment, a protective screen 18 is employed to prevent ice from falling into the duct.

It will be observed that the cross-sectional area of the warm air duct 22 is somewhat smaller than that of any other opening or passage in the path of air circulation. At this point in its travel, the density of the air, because its temperature here is highest, is appreciably less than at any other point. Therefore, due in part to the increased volume of air here, and in part to the decreased cross-sectional area of the air passage, the velocity of upward air movement through the duct 22 is relatively high. The kinetic energy of this upwardly moving column of warm air in duct 22 effectually counters any tendency of the colder and heavier air from the refrigerant compartment to flow downwardly through duct 22 and thus to impede the circulation of air throughout the refrigerator.

The bottom of the refrigerant compartment is slightly inclined so that it will drain toward the pipe 19, and the upper edge of the opening 14 is upturned, as shown at 20, to prevent water from the melting ice from flowing downwardly into the compartment 7. Sloping the bottom of the refrigerant compartment downwardly from the duct 22 toward the pipe 19 and locating the pipe 19 near the opening 14 contributes appreciably to the efficiency of my refrigerator. Cold air, like water flows "down hill", and the air in the refrigerant compartment, as it is chilled and condensed by contact with the ice, sinks to the bottom of the compartment and flows down the slope thereof toward the opening 14 so that rapid circulation through this compartment is

thereby facilitated. Likewise, sloping the top of the food-storage compartment upward toward the opening 16 into the warm air duct prevents any pockets of warm air at the top of this compartment and also facilitates air circulation. The bottom of the ice rack is also provided, over the opening 14, with a sweat baffle 21. The food compartments are closed by a door or doors 23, which are separate from the door or doors opening into the refrigerant compartment, and it is to be understood that the door 23 when closed fits closely against baffle 9 to prevent circulation of air therebetween.

In operation, a rapid and uniform circulation of air is maintained in the direction of the arrows as follows: The air in the refrigerant compartment being cooled by contact with the ice or other refrigerating element is thereby condensed and sinks to the bottom of this compartment from which it flows along or over the downwardly sloping bottom of flue or duct 13 to the opening 14 and thence downwardly through compartment 7 wherein the most highly perishable food products are stored; thence under the baffle 9 and upwardly through the food compartment 8. As the air contacts with the stored food it absorbs heat therefrom, is warmed and expanded and flows upwardly through compartment 8. It leaves the food compartment 8 through the duct or flue 22, passes through the protecting screen 18 into the refrigerant compartment where it is cooled and condensed and the cycle repeated.

Inasmuch as the air is cooled primarily by direct contact with the ice the advantages of having the duct 22 communicate with the ice compartment at a comparatively low elevation, say four or five inches above the ice rack, are apparent. By this arrangement, it is obvious that the ice cake 6 may be appreciably diminished in size by melting before it reaches a point so low that warm air passing over the top of baffle 16 does not come directly in contact therewith. Moreover, by locating the warm air duct at a point remote from the cold air outlet 14 and making the refrigerant compartment substantially greater in width than height, an extremely long path of travel is provided so that the air is thoroughly chilled by contact with the refrigerant. Another important feature is the use of heat-insulating material for baffle 17. This prevents the cooling of the air in duct 22 by direct conduction of heat through the baffle and thus prevents any tendency, from this cause, to retard or create a reverse air flow here.

While I have described my invention in its preferred embodiments, it will be understood that the words which I have used are words of description rather than of limitation and that changes within the purview of the appended claims may be made without departing from the true scope and spirit of my invention in its broader aspects.

What I claim is:

1. A refrigerator comprising a casing, heat insulated partitions dividing said casing into an upper refrigerant compartment extending across substantially the entire width of the casing and first and second food storage compartments below said refrigerant compartment; the first food compartment being substantially open at the top to provide direct communication with the lower portion of the refrigerant compartment to permit the free downward flow of cold air therefrom at relatively low velocity, and the second food compartment being substantially closed at

- the top but having a comparatively narrow flue communicating with the refrigerant compartment at a point intermediate the top and bottom thereof and remote from said first food compartment to permit an upward flow of warm air into the refrigerant compartment at relatively high velocity, whereby the kinetic energy of said upwardly moving warm air tends to prevent a counter flow of cold air from the refrigerant compartment into said flue, and air circulation throughout said refrigerator is maintained in one direction. 80
2. A refrigerator comprising a heat-insulated casing, a heat-insulated, transverse partition in the upper part of said casing extending substantially from side wall to side wall thereof and subdividing the interior into an upper refrigerant compartment having a greater width than height and a lower food compartment; said partition having an opening of substantial size near one end for the downward passage of cold air 85
- and a smaller opening immediately adjacent the opposite end for the upward passage of warm air; a heat insulated baffle extending downwardly from said partition intermediate said openings but adjacent the larger and dividing the food compartment into sub-compartments communicating in the lower zones thereof; and a second baffle of heat-insulating material extending upwardly from said partition at the edge of said smaller opening to form a comparatively low lip or dam for preventing a downward flow of cold air from the refrigerant compartment through said warm air passage. 90
3. The structure set forth in claim 1 in which the bottom of the refrigerant compartment is downwardly inclined toward the opening therein for the outflow of cold air and in which the top of that food-storage compartment in which the air flows upwardly is upwardly inclined toward the opening therein for the outflow of warm air. 95
